(57) **CLAIM**

The ornamental design for a faucet, as shown and described.

DESCRIPTION

FIG. 1 is a top, right-side, rear perspective view of a faucet showing the new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is an enlarged view of a portion 8 as shown in FIG. 2;

FIG. 9 is an enlarged view of a portion 9 as shown in FIG. 7; and,

FIG. 10 is another enlarged view of a portion 10 as shown in FIG. 7.

The broken lines in the figures depict environmental subject matter and form no part of the claimed design.
